UNITED STATES PATENT OFFICE.

HENRY B. ROBISCHUNG, OF KALAMAZOO, MICHIGAN, ASSIGNOR TO THE NATIONAL HOLLOW BRAKE BEAM COMPANY, OF CHICAGO, ILLINOIS.

DEVICE FOR SECURING BRAKE-HEADS TO BRAKE-BEAMS.

SPECIFICATION forming part of Letters Patent No. 442,138, dated December 9, 1890.

Application filed September 5, 1890. Serial No. 364,035. (No model.)

To all whom it may concern:

Be it known that I, HENRY B. ROBISCHUNG, a citizen of the United States, residing at Kalamazoo, in the county of Kalamazoo and State 5 of Michigan, have invented certain new and useful Improvements in Devices for Securing Brake-Heads to Brake-Beams; and I hereby declare the following to be a full, clear, and exact description of the same, reference being had to the accompanying drawings, in which--

Figure 1 is a plan view of a trussed metallic brake-beam, portions broken away, a supplemental attaching-block embodying my invention, and a brake-head and shoe, the attaching-block, brake-head, and shoe being in horizontal section. Fig. 2 is a side view of the supplemental attaching-block, brake-head, and shoe. Fig. 3 is a detached view of the brake-head. Fig. 4 is a rear or back view of the brake-head. Fig. 5 is an end view of an attaching-block embodying my invention, and Fig. 6 is a rear view of said attaching-block. Fig. 7 is a modification in which a 25 broken loop or two undercut lugs are used.

Like symbols refer to like parts wherever they occur.

My invention relates to the construction of supplemental attaching-blocks, whereby the 30 usual or common forms of brake-heads may be readily and securely attached to brake-beams of forms not originally intended for use with said heads. The common form of brake-beam heretofore in most general use 35 has been a wooden beam of substantially rectangular cross-section, and the approved form of brake-heads have consequently been generally formed with a rectangular recess or seat for the reception of the end of the brake-beam and with a back plate or laterally-projecting rear flanges (see Figs. 3 and 4) for attaching the head to the beam. Owing to the 40 different means employed for securing the shoe to the head, and for other reasons, said 45 brake-heads have sometimes a single central bolt-hole and sometimes two laterally-placed bolt-holes, as shown in the drawings, for bolting the head to the beam.

The devices of the present invention, while 50 of general utility for the purpose specified,

have been devised more especially for that class of the common form of brake-heads wherein two laterally-placed bolts are provided for.

The invention, generally stated, consists in 55 a supplemental attaching-block having a face-plate or table provided at one end with a loop, or overhanging lateral lugs the equivalent of the loop, adapted to receive one flange of the back plate of a brake-head and with a through-bolt or equivalent device at the other end for binding said back plate to the face-plate or table of the attaching-block, substantially as will hereinafter more fully appear.

I will now proceed to describe my invention 65 more fully, so that others skilled in the art to which it appertains may apply the same.

In the drawings, A indicates the beam, B the post or strut, and C the tension-rod or truss-rod, of any approved form of metallic 70 beam, the particular construction being immaterial, as the same forms no part of the present invention.

1 indicates the supplemental attaching-block, preferably of cup or box form, as shown, 75 though any form which will embrace the end of the metallic beam may be adopted.

The means for securing the supplemental attaching-block to the beam forms no part of the present invention, and may be, if desired, 80 the ends of truss-rod C with nut c and recess and lug d, as indicated on the drawings, or any other suitable means to meet any particular character of metal beam.

Formed with or attached to the supplemental attaching-block, in a plane which will stand parallel or substantially parallel with the axis of the beam A, is a table or face-plate 2, provided on its sides at or near one end with undercut lugs 3 3, (see Fig. 7,) which 90 may, if desired, be extended or joined to form a loop 3^a, (see Fig. 5,) which is the preferred form, as giving the greatest strength and security for the parts. These undercut lugs or the loop formed therefrom are intended to 95 receive one end of the back plate or laterally-projecting flanges a a (see Fig. 4) of the common brake-head.

Near the end of table or face-plate 2, opposite to loop 3^a and usually in the central line, 100

is a bolt-hole 4 for the reception of a bolt 5 or its equivalent, which, coacting with loop 3^a or lugs 3 3, binds the back plate *a a* of the brake-head firmly upon the table or face-plate 2.

When in use, the supplemental attaching-block 1 is first properly secured to the end of the metallic brake-beam. One end of back plate *a a* of the brake-head is then inserted under the undercut lugs 3 3 (or their equivalent, the loop 3^a) and moved endwise until the bolt-hole near the opposite end of the back plate *a* registers with the bolt-hole 4, after which the bolt 5 is inserted and the nut thereof tightened to bind the parts securely together.

In addition to the advantages of simplicity, durability, and facility with which the brake-head can be removed and replaced (the bolt 5 being to the outside) without disturbing the brake-beam the undercut lugs or loop-construction herein described enables the back plate to be shifted endwise, so that any common form of brake-head having two laterally-placed bolt-holes can be applied without drilling bolt-holes at special points in the face-plate or table of the attaching-block.

Having thus described my invention, what I claim, and desire to secure by Letters Patent, is—

1. A supplemental attaching-block for brake-beams, said block having a face-plate provided on its sides, at or near one end, with undercut lugs and at its opposite end with a clamp adapted to bind the back plate of a 3
brake-head to the said face-plate of the attaching-block, substantially as and for the purposes specified.

2. A supplemental attaching-block for brake-beams, said block having a face-plate 4 provided on its sides, at or near one end, with undercut lugs which unite over the plate to form a strap or loop, and having at the opposite end a bolt-hole for the reception of a clamp-bolt, substantially as and for the purposes specified.

In testimony whereof I affix my signature, in presence of two witnesses, this 30th day of August, 1890.

HENRY B. ROBISCHUNG.
